UNITED STATES PATENT OFFICE

171,576

PHONOGRAPH

Ben Birns, Rockville Centre, N. Y.

Application August 12, 1953, Serial No. 26,422

Term of patent 7 years

(Cl. D56—4)

To all whom it may concern:

Be it known that I, Ben Birns, a citizen of United States, residing at Rockville Center, in the county of Nassau and State of New York, have invented a new, original, and ornamental Design for a Phonograph, of which the following is a specification, reference being had to the accompanying drawing, forming part thereof.

In the drawing

Fig. 1 is a perspective view of a phonograph in closed condition standing up, showing my new design;

Fig. 2 is a top perspective view of the phonograph with the cover open;

Fig. 3 is a bottom plan view thereof.

I claim:

The ornamental design for a phonograph, as shown.

BEN BIRNS.
